NonFinal Office Action dated Dec. 30, 2016, U.S. Appl. No. 15/097,077, filed Apr. 12, 2016.

Primary Examiner — Derrick Holland

Assistant Examiner — Janice Patyk

(74) Attorney, Agent, or Firm — Alok Goel

(57) **CLAIM**

The ornamental design for a bottle, as shown and described.

DESCRIPTION

FIG. 1 is a perspective view of a bottle, showing our new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a back view thereof.

The broken lines in the figures illustrate portions of the design that form no part of the claimed design.

1 Claim, 4 Drawing Sheets
